UNITED STATES PATENT OFFICE.

DAMASE J. COTE, OF MANCHESTER, NEW HAMPSHIRE.

CASE-CLIP.

1,116,245.

Specification of Letters Patent.

Patented Nov. 3, 1914.

Application filed July 25, 1913. Serial No. 781,182.

To all whom it may concern:

Be it known that I, DAMASE J. COTE, a citizen of the United States, residing at Manchester, in the county of Hillsboro and 5 State of New Hampshire, have invented new and useful Improvements in Case-Clips, of which the following is a specification.

This invention relates to case clips and means for attaching the same.

10 One of the objects of the invention is to provide a simple and efficient clip adapted to be engaged over the wall of the pocket for holding the case against accidental displacement.

15 Another object of the invention is the provision of novel means for attaching the clip to the case in such manner that the clip is constantly held with firm pressure against the outside wall of the case, the clip having sufficient inherent resiliency to permit 20 spreading away from the case when desired.

Further objects of the invention will appear as the following description is read in connection with the accompanying drawing, 25 which forms a part of this application, and in which:—

Figure 1 is a front elevation. Fig. 2 is a side elevation showing a section of the pocket wall arranged between the clip and case. Fig. 3 is an enlarged detail sectional view taken through the clip and its attaching means.

Referring more particularly to the drawing, 1 represents an ordinary eye glass case 30 having a hinged spring actuated lid 2. This lid is usually formed of metal and covered on its exterior surface with leather or other similar material and usually lined with plush, chamois or the like, the lining in this

instance being indicated at 3. Adjacent one 40 end and central of the lid the same is provided with a raised boss 4 produced by punching out the metal, as shown. This boss is centrally apertured and passing through the aperture is a bolt 5 upon which 45 a clamping nut 6 is threaded, this nut being arranged between the lid and the lining and seated in the depression 7 produced by forming the boss, so that when the lining is secured over the same a substantially even 50 inner surface is produced.

The bolt is provided with a head 8 recessed on its under side, as shown at 9, to substantially fit the boss and wound around the bolt and seated between the head and 55 the upper end of the boss are the terminals of the spring clip 10. In this manner the terminals of the clip will be arranged in the depression of the head and the depending outer edges will bear upon the clip and hold 60 the same firmly against the case lid.

What is claimed is:—

In combination, a case lid having an outwardly projecting hollow boss, a bolt passing through the boss, a clamping nut 65 threaded on the bolt and seated in the hollow of the boss, a head on the bolt having a hollowed out portion to fit the boss and a spring clip having its terminals wound around the bolt and arranged in the hollowed out portion of the head.

In testimony whereof I affix my signature in presence of two witnesses.

DAMASE J. COTE.
